DESIGN FOR A COMBINED VENDING MACHINE AND CONDIMENT STAND OR SIMILAR ARTICLE

Julius Kunen, New York, N. Y.

Application October 23, 1935, Serial No. 59,182

Term of patent 7 years

To all whom it may concern:

Be it known that I, Julius Kunen, a citizen of the United States, residing in Kings County, city and State of New York, have invented a new, original, and ornamental Design for a Combined Vending Machine and Condiment Stand or Similar Article, of which the following is a specification, reference being made to the accompanying drawing, forming part thereof.

In the drawing,

I claim:

The ornamental design for a combined vending machine and condiment stand or similar article substantially as shown.

JULIUS KUNEN.
